BY
his ATTORNEY

UNITED STATES PATENT OFFICE.

ELLSWORTH F. STOUT, OF RICHMOND HILL, NEW YORK.

HEATER.

Application filed October 17, 1918. Serial No. 253,572.

To all whom it may concern:

Be it known that I, ELLSWORTH F. STOUT, a citizen of the United States of America, residing at Richmond Hill, county of 5 Queens, State of New York, have invented certain new and useful Improvements in Heaters, of which the following is a specification.

This invention relates to heaters.

10 More particularly, the invention relates to heaters for heating water and other fluids. In the most preferred form of the invention, means are provided in combination with a set of spiral heating coils, for additionally 15 heating the heated water delivered by such set or sets of spiral heating coils, the whole being arranged to reduce losses of heat to a minimum.

Further features and objects of the invention are more fully set forth in the following description and the accompanying drawing, showing in vertical elevation partly 20 in vertical section, one embodiment of the invention.

25 Referring to the drawings, 1 represents the burner of any approved type, and 2 the casing, usually provided with the outlet 3, for the discharge of the products of combustion, which outlet may be varied or modified 30 according to circumstances, as will be understood.

35 4 represents a set of heating coils, suitably connected at one end 5 with the cold water supply pipe 6. The discharge end of such a set of spiral coils 4 is indicated at 7.

To such discharge 7 is connected the additive heater 8 comprising the main chamber 9 extending from a region in adjacent heating relation to the burner 1 upwardly, and 40 preferably through the outlet 3 of the casing 2, said additive heater 8 being connected at its upper end to the riser 10 and thus with the boiler or reservoir 11. The discharge pipe of the reservoir 11 is indicated at 12.

45 Preferably, also, the connection of the main chamber 9 with the discharge terminal 7 of the heating coils 4, is effected by means of the pipe 13 arranged as a chamber disposed inwardly or within the additive heater 50 chamber 9 and discharging at its lower end 14 into the lowermost portion 15, as indicated by the arrows 16.

Such preferred form of the invention provides the reduced region 17, of more or less 55 annular formation, immediately adjacent the outer wall of the additive heating chamber

9, whereby a relatively thin layer of water or other fluid is subjected directly to the heat of the flame of the burner 1, and provides further for the passage of the water 60 or other fluid, previously heated in the coils 4, through the chamber 13 surrounded by water or other liquid in the additive heating chamber 9 of higher temperature.

To attain more fully the aforesaid results, 65 the chambers 9, 13, either or both, are corrugated, as by threading, or otherwise provided with projecting, relatively thin portions 18, to increase the transference of heat. For simplicity of manufacture and assembly, the outer chamber 9 and inner chamber 70 13 may be formed of pipe of proper diameters, the outer pipe being closed at its lower end by the cap 19 and connected at its upper end to the riser 10 by means of the reducer 75 20. The connection of the discharge end 7 of the coils 4 may be simply attained by means of the pipe section 21, threaded at one end into the openings 22, 23, respectively of the inner pipe 13 and outer pipe 9, and connected with 7 by means of the elbow 24, 80 nipple 25 and the union 26.

85 Preferably, as shown, the connection of the section 21 with the inner chamber or pipe 13 is effected by means of the reducer 27, connected at its larger opening 28 with the chamber or pipe 13 and its smaller opening 29 communicating interiorly of the outer reducer 20, whereby upon lighting the burner 1, heated water is supplied to the 90 boiler or reservoir 11 initially jointly from the chamber 9 and the coils 14. Such arrangement is advantageous in that a larger quantity of heated water is supplied promptly after first lighting the burner. 95

Under conditions of continued heating by the burner, by reason of the additive heater 9 being disposed in the region of higher temperature as compared with the coils 4, the effective temperature of the water in the 100 additive heater chamber 9 becomes more and more increased and accordingly upon rising upwardly within the superheater 9 and thence into the riser 10, causes the water discharging through the pipe 21, to 105 traverse in increasing proportion downwardly through the pipe 13, and accordingly in decreasing proportion directly through the opening 29 into the riser 10. The reduced extent of opening of the opening 29 110 facilitates such differential action.

The aforesaid action of quickly deriving

warm water in large quantity upon initial lighting of the burner and materially increasing the temperature or additively heating the water upon continued lighting of the burner, is particularly effective when the water is caused to flow through the discharge 12, i. e., by turning on the faucet.

The invention is applicable in use as an attachment of the additive heater to an ordinary hot water heater provided with such set or sets of spiral coils, such attachment being readily effected without disturbing the water heater when the latter has been previously installed.

15 Whereas I have described my invention by reference to specific forms thereof, it will be understood that many changes and modifications may be made without departing from the spirit of the invention, as defined by the 20 appended claims.

I claim:

1. A water heater comprising a burner, a casing, a vertically extending hollow coil for the passage of the water and disposed above 25 said burner, a hollow passage member disposed above said burner and within said coil, an outflow passage member for the outflow of heated water from said coil and from said

hollow passage member and a T-connection 30 communicating with said coil and said hollow passage member and said outflow passage member.

2. A water heater comprising a burner, a casing, a vertically extending hollow coil for the passage of the water and disposed above 35 said burner, a vertically extending passage member disposed above said burner and within said coil, an outflow passage member and a T-connection connecting said coil and said hollow passage member in common with 40 said outflow passage member.

3. A water heater comprising a burner, a casing, a vertically extending hollow coil for the passage of the water and disposed within 45 said casing above said burner, a tube closed at its lower end, a second tube extending within said first named tube and communicating at one end with the interior of said first named tube, an outflow passage member for the outflow of the heated water and a 50 T-connection between said coil, the other end of said second named tube and said outflow passage member.

In testimony whereof I have signed this specification this 14th day of October, 1918.

ELLSWORTH F. STOUT.
